[57] CLAIM

The ornamental design for an electronic calculator with voice clock, as shown and described.

DESCRIPTION

FIG. 1 is a bottom plan view of an electronic calculator with voice clock showing our new design;

FIG. 2 is a top plan view thereof;

FIG. 3 is a rear elevational view thereof;

FIG. 4 is a front elevational view thereof;

FIG. 5 is a left side elevational view thereof;

FIG. 6 is a right side elevational view thereof;
FIG. 7 is a top plan view thereof with the cover open;
and

FIG. 8 is a left, bottom and rear perspective view thereof;

FIG. 9 is a right, front perspective view thereof, with the cover shown in the open position.
